FISHING ROD

Maurice J. Fletcher, Arlington, Va.

Application March 8, 1949, Serial No. 1,294

Term of patent 14 years

(Cl. D31—4)

To all whom it may concern:

Be it known that I, Maurice J. Fletcher, a citizen of the United States, residing at Arlington, State of Virginia, have invented a new, original, and ornamental Design for a Fishing Rod, of which the following is a specification, reference being had to the accompanying drawing, forming part thereof.

Fig. 1 is a side view of a fishing rod in extended position, showing my new design.

Fig. 2 is a side view of the rod retracted.

Fig. 3 is a top plan view of the rod extended.

Fig. 4 is a bottom plan view of the rod extended.

I claim:

The ornamental design for a fishing rod, substantially as shown.

MAURICE J. FLETCHER.
